JAMES P. SCOVILL, OF WYOMING, OHIO, ASSIGNOR TO THE TROJAN MACHINE COMPANY,
OF TROY, NEW YORK, A CORPORATION OF NEW YORK.

TOBACCO-STEMMING ROLL.

1,145,441.

Specification of Letters Patent. Patented July 6, 1915.

Application filed August 19, 1912. Serial No. 715,807.

To all whom it may concern:

Be it known that I, JAMES P. SCOVILL, a citizen of the United States, residing at Wyoming, in the county of Hamilton and State of Ohio, have invented certain new and useful Improvements in Tobacco-Stemming Rolls, of which the following is a specification.

My invention relates to an improvement 10 in stripping rolls for tobacco stemming machines of the character disclosed in my application, Serial No. 690,883, filed April 15, 1912.

One of the objects of the invention is to 15 improve the efficiency of the rolls.

Another object of the invention is to produce a construction and arrangement of 20 stripping instrumentalities which will not entwine the stems around the rolls in the operation of stripping.

Another object of the invention is to cheapen and simplify the construction.

The features of my invention are more 25 fully set forth in the description of the accompanying drawings, forming a part of this specification in which:

Figure 1 is a longitudinal section through my improved roll. Fig. 2 is a transverse section. Fig. 3 is a detail perspective view 30 of one end of one of the wire containing plates.

1 represents the cast roll suitably cored to receive the operating shaft.

2 represents a series of converging walls 35 radially projected from the hub of the roll at suitable intervals to form a series of channels 3 defined by said converging walls. In each of said channels extending radially across the roll, is secured a closely compacted fiber or brush 4, forming a relatively soft, segmentally disposed series of resilient strippers. The roll is formed with a series of plane surfaces 6 between said segmental series of brushes, which serve as 45 seats for the instrumentalities to be secured to the roll between said fibrous components.

5 represents a plate formed of a sheet of metal folded upon itself and having orifices 50 7 along the folded margin. 8 represents resilient wires secured between the folds of said metal plate and projecting through said orifices and extending outwardly at right angles to the plate. Upon each of said seats 55 6 is placed one of said plates 5 with the

wires 8 extending radially from the roll and disposed closely against the adjacent outer edges of the series of segmental brushes. The wires are embedded into the fibers upon the advancing lateral edges of the brushes 60 in a direction relative to the rotation of the roll, so that in operation the resilient wire stripping elements first attack the leaf and then yield rearwardly into the resilient fibrous stripping elements becoming buried 65 therein, so that a relatively harsh and soft resilient stripping action is thus administered to the leaf passing between the rolls.

9 represents a binder plate, one of which is secured to each of the plates 5 by screws 70 10, said binders being spaced from the plates 5 by the leather washers 11. Preferably, the advancing edge of each binder has secured thereto a leather projecting strip 12, so that when said binders are in 75 place, the rear or metallic edge will force the wires compactly into the fibers at the advancing edge of the stripping segments, while the leather edges of the binders will bear against the fiber edges of the adjacent 80 segment so as to prevent the fibers from being severed when subjected to the stresses of the stemming operation. These binders not only closely compact the stripping elements of each two adjacent segments, but 85 they also serve to limit the depth of stem embedding into the stripping elements, which project radially beyond the outer faces of said binders. Preferably, the roll is tapered toward one end to produce a stem 90 access between the rolls. Also, preferably, disks 13 are secured to the ends of the rolls to assist in holding the binders and plates in position between the stripping segments. Also, I preferably grind or form 95 each of the stripping segments so that the advancing edges, where the wires are embedded into the fibers are lower radially than the rear edges of the segments, where there are no wires. I have found this 100 method of embedding the resilient wire or harsh stripping elements into the fiber or relatively soft stripping elements, to be very advantageous, as the wires dip rearwardly 105 into the fibers, enabling the fibers, while administering a delicate stripping treatment, to clear the leaf product from the wires so as to prevent the stems and leaves from becoming entwined around the rolls. This result, which is important, is also partly due 110

to the fact that I use the rolls just described as the lower members of the pairs of stripping rolls, the upper members comprising a roll of the same general construction, 5 without any wire stripping elements. These rolls are set in intermeshing relationship in a manner corresponding to the arrangement of the rolls described and claimed in my said prior application.

10 It will be seen that the seats, wire plates, and binders lie in planes transverse to the radial line of the roll represented by the stripping elements.

Having described my invention, I claim:—

15 1. A tobacco leaf stemming roll, comprising a segmental series of closely compacted fibers, and resilient wires disposed along the outer edges of said segments, said fibers and wires constituting stripping elements 20 of differential resilience radially projecting from the roll.

2. A tobacco leaf stemming roll, comprising a segmental series of closely compacted fibers, and resilient wires disposed adjacent 25 the advancing edges of the fibrous segments in their direction of rotation, enabling said wire components to attack the leaf so as to yield rearwardly and become buried within the fiber body.

30 3. A tobacco leaf stemming roll, comprising a segmental series of closely compacted fibers, resilient wires disposed along the advancing edges of said fibrous segments in

the direction of rotation, and members between said segments serving to compact said 35 wire and fiber resilient stripping elements and terminating below the extremities thereof to limit the stem embedment.

4. A tobacco leaf stemming roll, comprising a segmental series of closely compacted 40 fibers, resilient wires compacted against the advancing edges of said segments in the direction of roll rotation, and a series of plate binders secured between the stripping segments in directions transverse to the radially extending stripping elements, and below the extremities thereof.

5. In a tobacco leaf stemming roll, a hub structure, comprising an axially extending 50 series of channels, seat surfaces between said channels extending in transverse planes to the radial lines of the roll, fibers secured within said channels, wire holding plates secured upon said seats, with resilient wires closely compacted against the advancing 55 edges of the fiber segments, and binding plates secured upon said wire holding plates, and parallel thereto, serving to compact the wire and fiber resilient elements and terminating below the extremities thereof.

In testimony whereof, I have hereunto set my hand.

JAMES P. SCOVILLE.
